UNITED STATES PATENT OFFICE.

JACOB W. KRAUS, OF STERLING, OHIO.

CULTIVATOR.

SPECIFICATION forming part of Letters Patent No. 443,919, dated December 30, 1890.

Application filed June 12, 1890. Serial No. 355,259. (No model.)

To all whom it may concern:

Be it known that I, JACOB W. KRAUS, a citizen of the United States of America, residing at Sterling, in the county of Wayne 5 and State of Ohio, have invented certain new and useful Improvements in Cultivators, of which the following is a specification, reference being had therein to the accompanying drawings.

- 10 This invention pertains to certain new and useful improvements in cultivators, having for its object the provision of simple and highly-efficient means for readily operating the drag-frames simultaneously or separately 15 and for raising and lowering the same from the ground and to swing them apart or together laterally or parallel. By thus constructing my improved cultivator one man is enabled to operate a machine with ease, and 20 it may be operated while the driver is walking behind it or riding on the machine.

The invention therefore comprises the construction, combination, and arrangement of the parts substantially as hereinafter fully 25 set forth, and shown in the accompanying drawings, in which—

Figure 1 is a side elevation of my improved cultivator. Fig. 2 is a vertical section of my invention. Fig. 3 is a rear elevation of one 30 side thereof. Fig. 4 is a horizontal section of the tooth-frame. Fig. 5 is a detail view of the axle and the means for securing it to the T-shaped portions. Fig. 6 is a sectional view of the spring cultivator-tooth, and Fig. 7 is a 35 detail sectional view of the spring ratchet-lever. Fig. 8 is a plan view of the cultivator, and Fig. 9 is a front elevation of the same.

In the embodiment of my invention, A represents the cultivator-frame, composed of the 40 parallel side bars *a a* and the front cross-bar *a'*. Journaled to the under side of bars *a a*, near the rear end thereof, is the axle B of an approximately inverted-U shape and having its short arms *b b* projected into vertical 45 low cylinders *b' b'*, integral with inverted-T-shaped portions C C, in which they are pivotally secured by means of inclined rods *b²* *b³*, connected at one end to the bars *a a* and projected through horizontally-aligned slots 50 *b³ b⁴* in cylinders *b' b'* and through orifices *b⁴ b⁵* in said short arms *b b*. Upon the outer

horizontal ends of the T-shaped portions C C the carrying-wheels are pivotally secured.

The inner horizontal ends of the T-shaped portions C C are grooved at *c c*, in which 55 grooves the driver or operator places his feet. Cast integral with the inner horizontal arms of the T-shaped portions are plates *c' c'*, having a series of orifices therein, the purpose of which will be described farther on. To the 60 upper ends of the vertical cylinders *b' b'* of the T-shaped portions C C, and cast integral therewith and at right angles thereto, are horizontal arms or levers *c² c²*, the ends of which are connected by a link or rod *c³*, the 65 object of which is, in connection with said levers or arms *c² c²*, to cause the wheels when moved laterally to move parallel. Thus constructed it will be seen that the axle proper is formed in three castings, viz: the axle B 70 and the T-shaped portions C C. Said T-shaped portions connect the inner and outer horizontal arms, the plates having the series of orifices therein, the vertical cylinders, and the right angular levers. 75

D D are the drag-frames, composed of two bars *d* and *d'*, converged inward and connected near their center at *d²* and flared at both ends, the rear ends running parallel with one another, and are braced by a cross-strip *d³*. 80 The spring cultivator-teeth E are connected to said parallel bars and secured rigidly between the lower ends of two inclined parallel strips *e e*, pivoted at *e' e'* to one of the bars *d d'* of the drag-bars. Converging toward 85 strips *e e* and connected at *e² e²* rigidly to the end of one of the bars *d d'* is a corresponding strip *e³*, between the lower ends of which is pivoted near its center a strip *e⁴*, pivoted between the parallel strips *e e* at *e⁵*, and having a curved arm *e⁶*, formed on its upper end, which engages a notch *e⁷* in one of the bars *d d'*. Connected to the strip *e⁴* at *e⁸* is a rod *e⁹*, which engages a spring *e¹⁰*. Secured to the under side of one of the bars *d d'* is a socket 90 *e¹¹*, projected downwardly therefrom. Thus constructed it will be seen that when the tooth or shovel strikes a rock or other similar impediment in its course the spring is contracted, the tooth swung backward and consequently elevated, thus allowing it to pass over the obstruction. 100

Adjustably connected to a vertical bar f and to the cross or bracing strip d^3 is an ordinary plow-handle f' , which may be readily connected in case the operator is walking behind the machine, or it may be used when he is riding thereon.

Bars d d' , composing the drag-frame D D, as has hereinbefore been mentioned, are flared at their forward ends and are connected by a rod g , having a sleeve g' thereon, the rod g being projected at its inner end through the lower end of a supporting rod or bar g^2 , rigidly connected to the under side of the cross-bar a' of the frame A, and through the lower end of a strip g^3 , pivoted at g^4 to the front ends of bar a' . Projected vertically and inclined inwardly from sleeve g' at its outer end is a lever g^5 , having connected to its center by one end a link or rod h , which extends backward horizontally and is connected by its hooked end to the plates $c' c'$ of the T-shaped portions of the axle-beams C' C'. To the upper end of the lever g^5 is connected one end of a rod or link h' , extending rearwardly in a horizontal position and connecting with the lower end of the lever H on one end of the cross rod h^2 , journaled upon the under side of bars $a a$ and extending from side to side of the frame A parallel with the main axle-beam B. The cross-rod h^2 is projected at its opposite end into a right-angled arm h^3 , arranged in alignment with the lower end of the lever H and having connected to it a link h' . The lever H extends upward above its pivotal point and is designed to engage a semicircular ratchet-bar h^4 , its extreme upper end terminating in a handle h^5 . Thus it will be seen that by throwing the lever H forward the drag-bars D D will be thrown apart, and by throwing it backward the distance between the rear ends of the bars will be lessened, or by pressing upon the inner horizontal ends of the supplemental axle-beams the bars will be thrown from side to side parallel to each other.

Connected to the rear ends of frame-bars a is a semicircular ratchet-bar designed to be engaged by a pawl i on lever I, pivoted at its lower end to a rod i' , projected from the inner sides of bars $a a$ and inclosed by an approximately-V-shaped casing l , also pivoted upon rod i' , said casing having in its sides a series of orifices, and having a rod m^8 running across its upper open end, against which the upper end of an approximately-V-shaped spring m bears, said spring being coiled around a sleeve m^x , between the sides of the casing l , and on the rod i' , and its other end bears against the outer side of the lever I and against the front face of a lug l^3 thereon.

The purpose of the lever I is to raise and adjust the drag-frame.

Projecting forwardly from the casings l are arms m' , jointed to the upper ends of bars m^2 , reaching down through and having lateral portions m^3 at their lower ends adapted to

engage keepers m^4 , provided on the bars d , whereby is effected the vertical adjustment of the drag-frames. The bars m^2 are each provided with a notch n , to permit, by elevating either one or the other of the drag-frames, the engagement of the lower edge of the respective keeper with said notch for the retention in an elevated position whichever one of said drag-frames whose tooth it is or may be desired to take out of operation.

Pivoted on the rods g^2 g^3 , connected to the under side of cross-bar a , are levers o o , connected at their ends by a rod or link o' . These levers have connected integral therewith and projected vertically downward at right angles thereto a concave strip o^2 , which conforms to the periphery of rod g^2 , on which it turns, and projected from the lower end of said concave strips o^2 o^3 at right angles thereto are draft-levers o^3 o^4 , when in their normal position being in alignment with cross-piece a . To the ends of these levers the whiffletrees or singletrees are secured, the object of this part of my cultivator being to form a perfect draft-equalizer in connection therewith.

In adapting my cultivator as a riding cultivator a modified form of mechanism is used in raising and lowering the drag-bars, in that, in lieu of the cam-arm m' and the bar m^2 , I substitute a connecting rod or arm m^6 , which is pivotally connected to the casing l by means of bolt m^8 . From this construction it will be seen that when the lever I is adjusted the whole force of the V-shaped spring m is directed or bears against the rod m^6 , which in turn presses the drag-bar downward. By this construction it will be seen that the time or labor of the driver or operator is not taken up by the need of pressing downward upon the lever or upon the drag-bars, while the machine is adapted for work in undulating ground.

Having thus fully described my invention, what I claim, and desire to secure by Letters Patent, is—

1. A cultivator having its frame supported upon an approximately-inverted-U-shaped axle, the parallel ends of which are pivotally secured in vertical cylinders of the inverted-T-shaped portions by means of rods projected through horizontally-aligned slots in the sides of the vertical cylinders and through corresponding orifices in the lower free ends of the U-shaped axle, substantially as shown and described.

2. A cultivator having the inverted-U-shaped axle and inverted-T-shaped portions pivotally connected by means of rods projected through horizontally-aligned slots in the cylinders of the T-shaped portions and through corresponding orifices in the ends of the U-shaped axle, substantially as shown and described.

3. In a cultivator, the combination, with the shovel-standard and its beam, of the spring-actuated rod held in a support or guide upon

the under side of the beam and connected to the jointed or toggle brace secured to said beam and standard, substantially as set forth.

4. In a cultivator, the spring-actuated lever I and its casing l, having the series of orifices in its sides pivoted at its lower end and carrying integral therewith the lever or cam-arm m', in combination with the drag-frame and the bar m², having a projection bearing against the under side of said drag-frame, substantially as shown and described.

5. In a cultivator, the spring-lever I, having a pawl i on one side thereof and the lug l³ on

its opposite side, against which and the side of the lever one end of an approximately-V-shaped spring bears, said spring m being coiled at its lower end about a sleeve and having its other end bearing against a cross rod or pin m³ in the front of the inclosing-casing, substantially as shown and described.

In testimony whereof I affix my signature in presence of two witnesses.

JACOB W. KRAUS.
